UNITED STATES PATENT OFFICE.

KARL ALFRED RAGNAR JOHANSON, OF STOCKHOLM, SWEDEN, ASSIGNOR TO NYA
AKTIEBOLAGET SVENSKA AUTOMATEFABRIKEN, OF STOCKHOLM, SWEDEN.

APPARATUS FOR CHECKING WORKING-TIME.

1,235,519.

Specification of Letters Patent.

Patented July 31, 1917.

Application filed August 26, 1912. Serial No. 717,196.

To all whom it may concern:

Be it known that I, KARL ALFRED RAGNAR JOHANSON, a subject of the King of Sweden, and a resident of Stockholm, Sweden, have 5 invented new and useful Improvements in Apparatus for Checking Working-Time, of which the following is a specification, reference being had to the drawings accompanying and forming a part hereof.

10 My invention relates to improvements in apparatus for checking working time of the type used for printing cards inserted into the apparatus. The object of my invention is to construct an apparatus which shall 15 print direct upon the card the amount of time used for the work, so that no calculating operation shall be necessary.

To gain this object my invention consists chiefly in a time checking apparatus comprising 20 a frame arranged to receive a card, two typewheels rotatable relatively to the frame and relatively to one another journaled in the frame and arranged to print the card, and a clockwork coupled between the wheels 25 and arranged to turn one wheel relatively to the other one. The card is inserted into the apparatus when the work is started and is then printed by only the first wheel. When the work is finished the card is again 30 inserted and is then printed by both the wheels, the second wheel printing upon the card the time elapsed between the two insertions, said time being directly proportional to the angle by which the two wheels 35 have been rotated relatively to one another. At the first insertion of a card the second wheel is always returned to its zero position and the first wheel marks the card with a control figure. At the second introduction 40 of the card the first wheel is turned until it prints again the same control figure upon the card, while the second wheel prints the time consumed for the work.

My invention is illustrated in the accompanying drawings, in which Figure 1 is a 45 vertical cross-section of the apparatus, the section being taken on the line A—B of Fig. 2. Fig. 2 is a vertical cross section taken at right angles to the section shown in Fig. 1. Fig. 3 shows the slots in which the cards are inserted as viewed from above, and Fig. 4 illustrates a card as printed by the apparatus. Fig. 5 and Fig. 6 show details 50 of the apparatus.

55 Referring to the drawings, 1 represents

the frame or casing of the apparatus, 2, 2 represent bearings in which the shaft 3 is journaled, and 4 a crank fastened to the shaft. To the shaft 3 are fastened the two wheels 5 and 6, the wheel 5 inside of the 60 casing, and the wheel 6 between the casing and the crank outside of the casing. Inside of the casing are two wheels or disks 7 and 8 mounted rotatably on the shaft 3. The wheel 5 is attached by rods 9 to a disk 10 65 fastened to the shaft, so that the wheel 5 together with the disk 10 will form a drum fastened to the shaft 3.

Within this drum is an electromagnet 12 fastened to the bar 11. One end of the 70 armature 13 of this electromagnet is fastened to the lever 14 which is fulcrumed on the shaft 15, fastened between wheel 5 and disk 10, the lever 14 being guided by a tube 16 surrounding the shaft 15. The spring 17 75 acting on the lever 14 serves to keep the armature 13 normally at a distance from the electromagnet. Upon a stud 20, fastened to the lever 14, is loosely mounted a pawl 18 by a spring or the like held in engage- 80 ment with the ratchet wheel 19 which is fastened to the wheel 7, the stud 20 extending through a slot 21 provided in the edge of the disk 10.

When the electromagnet 12 is energized it 85 will attract its armature 13 so that the lever 14 is turned counter-clockwise in Fig. 1, and the pawl 18 will turn the wheel 7 as much as one tooth of the wheel 19 relatively to the wheel 5. Electric current is conveyed to the 90 electromagnet through the contact spring 22 insulated from the frame at 23 and resting against a contact ring 24 fastened to the shaft 3 but insulated therefrom. One end of the winding of the electromagnet is fas- 95 tened to the ring 24, its other end being connected to the shaft 3 and thus to the frame. The closing of the electric circuit may preferably be effected through a master clock in common for a number of such apparatus as 100 here described in such manner that an impulse of current is sent through the electromagnet at regular intervals—say every 15 minutes. The circumference of the wheel 7 is provided with types for printing every 105 quarter of an hour. The wheels 5 and 6 have types for printing control figures, and the wheel 8 carries types for printing the names of all the week days. To the wheel 8 is fas- 110 tened a cogwheel 25 engaging a pinion 26

which is to be turned by means of a key, not shown on the drawing.

A card 27 such as shown in Fig. 4 is given to every workman who is to do any certain work. Two slots 28 and 29 are provided in the casing obliquely in relation to one another as shown in Fig. 3. When the card is inserted into either of these slots it will rest upon a support formed by the rib 30 located 10 within the casing at a height which depends on the position of the wheel 8. The rib 30 is fastened to one end of the lever 32, fulcrumed at 31, the other end of the lever being acted upon by the eccentric 33 fastened to wheel 8. Upon turning the wheel 8 a step in the direction of the arrow in Fig. 6 the rib 30 will be lifted through a distance equal to the distance between two lines in the card 27.

20 For printing a card the lever 35 is provided, fastened to the shaft 34. One end 36 of this lever is so arranged as to limit the upward movement of the lever; to its other end is joined the arm 37 which supports a 25 hammer for bringing the card in contact with the types on the wheels. The hammer consists preferably of pieces of rubber 39 held in a channel bar 38 opposite the faces of the typewheels. The spiral spring 40 30 serves to keep the lever 35 in the position shown in Fig. 1. Upon the end of shaft 34 outside of the casing is fastened the crank 41 and a handle.

Before the workman commences the work 35 he inserts his card into the inner slot 28 and so that it rests upon the rib 30. By means of the crank 4 he turns the wheel 7 back to its zero-position which is determined by the pawl 42 joined to the bearings 2 and 20 engaging the heel 43 upon the wheel 7. The workman then depresses the lever 41 and lets it go suddenly whereupon the spring 40 throws the hammer against the card. Upon the card will then be printed the name 45 of the day by the wheel 8 and the control figure for instance 130 by the wheel 5, while the wheel 7 will print nothing, the location of the slot 28 being such that the card does not reach the wheel 7. The workman now 50 takes out the card and preserves it until the work is completed.

In the meantime the apparatus may be used by other workmen, care being taken that the wheel 7 be always returned to its 55 zero position.

When the work is completed the workman again inserts his card into the apparatus but this time into the slot 29, when the card will stand opposite all of the wheels 8, 5 and 7. 60 He now turns the crank 4 until the control figure on the wheel 6 which corresponds to the control figure on his card—thus in the case assumed the figure 130—will come opposite the index 44 fastened to the frame. The 65 types on the wheels 6 and 5 are so placed

that the corresponding figure 130 on the wheel 5 will now be opposite the hammer 39. Therefore when the workman again depresses and releases the lever 41 the card will again be printed with the name of the 70 day and the control figure 130, and in addition thereto will be printed by the wheel 7 the time elapsed since the previous use of the apparatus by the same workman for the same card, that is the time which he used 75 for that particular work. For during this time the wheel 7 has been turned by the electromagnet 12, and by the master clock controlling it, through just such an angle relatively to the wheel 5, that the types 80 which state the said time are opposite the hammer when the wheel 5 is so turned that the control figure 130 as before stands opposite the hammer.

The types of the wheels may be such 85 that they mark the figures, etc., direct on the cards or a color ribbon may be arranged between the types and the cards, the ribbon being fed by suitable mechanism similar to the mechanism used on typewriters for such 90 purpose.

In order that the apparatus shall operate in the manner described it is of course necessary that the wheel 7 must not turn relatively to the wheel 5 except at the moments 95 when the electromagnet 12 becomes excited and attracts its armature. In order to prevent any accidental turning of the wheel 7, two studs 45 and 46 are fastened to the lever 14 (Fig. 5) in such way that they will entirely stop the wheel 7 from moving except at the moment when the armature becomes attracted. When the lever 14 occupies its normal position (shown in full drawn lines in Fig. 5) the stud 46 lies close 100 to a tooth in the wheel 19 and therefore prevents the wheel from turning in the direction of the arrow. When the armature is attracted and moves the lever 14, the stud 46 will release the wheel, while the stud 45 105 will immediately engage the wheel and perform the same function as did the stud 46 to prevent the wheel from turning in the direction of the arrow more than one tooth at a time. Any motion of the wheel in the opposite direction is prevented by the pawl 18. When the handle 4 is rotated in one or the other direction the wheels 6 and 5 secured to the shaft 3 will, of course, be rotated as well as the magnet 12 secured to the wheel 120 5. By means of the studs 45, 46 and the pawl 18 on the lever 14 of the armature 13 the wheel 7 will be brought to rotate with the shaft and the wheels 6 and 5.

I do not limit my invention to the particular construction shown in the drawing, for this construction may be modified in many respects and still come within the scope of my claims. For instance the wheel 7 may be divided up into several smaller 125 130

wheels, and the number of electromagnets correspondingly increased. Instead of the electromagnet and its associated parts a clockwork may be provided within the apparatus, and arranged to turn one of the wheels at constant speed relatively to the other one.

Having thus described my invention, what I claim is:

- 10 1. In a time checking apparatus, the combination of a frame arranged to receive a card, a shaft freely turning in the frame, a typewheel secured to and turning with the shaft, a second typewheel on the shaft rotatable relatively to the first-named wheel, said typewheels being arranged to print the card, and a clockwork secured to one of the wheels and arranged to turn the second typewheel relatively to the other one, substantially as 15 and for the purpose described.
- 20 2. In a time checking apparatus, the combination of a frame arranged to receive a card, a shaft freely turning in the frame, a typewheel secured to and turning with the shaft, a second typewheel on the shaft rotatable relatively to the first-named wheel, said typewheels arranged to print the card, an electromagnet secured to the first-named wheel and arranged to turn the second wheel 25 relatively to the same, and means for conveying electric current to the electromagnet, substantially as and for the purpose described.
- 30 3. In a time checking apparatus; the com-

bination of a frame arranged to receive a card, a shaft freely turning in the frame, a typewheel secured to and turning with the shaft, a second typewheel on the shaft rotatable relatively to the first-named wheel, said typewheels arranged to print the card, an electromagnet secured to the first-named wheel and having an armature, an operative connection between the armature and the second wheel, and means for conveying electric current to the electromagnet, substantially as and for the purpose described.

4. In a time checking apparatus, the combination of a frame arranged to receive a card, a shaft freely turning in the frame, a typewheel secured to and turning with the shaft, a second typewheel on the shaft rotatable relatively to the first-named wheel, said typewheels arranged to print the card, an electromagnet secured to the first-named wheel and having an armature, a connection between the armature and the second wheel for turning the same relatively to the first-named wheel, means for locking the second wheel to the armature when not turned by the same, and means for conveying electric current to the electromagnet at regular intervals, substantially as and for the purpose described.
